Hubbell, Incorporated, Bridgeport, Conn., a corpora-
tion of Connecticut

Filed Oct. 23, 1968, Ser. No. 14,129

Term of patent 14 years

Int. Cl. D13—03

U.S. Cl. D26—1

FIG. 1 is a perspective view of the electrical wiring device or similar article embodying my new design showing the top, one side and one end;

FIG. 2 is a perspective view thereof showing the top, the other side and the other end;

FIG. 3 is an end elevational view showing said one end;

FIG. 4 is a side elevational view thereof;

FIG. 5 is an end elevational view of said other end; and

FIG. 6 is a sectional view taken substantially along line 6—6 of FIG. 4 on an enlarged scale to more clearly show the ribbed outer surface of the body section.

The broken line showing of a conventional conductor in FIGS. 1 and 2, and of conventional screws in FIGS. 3, 4, and 5 is for illustrative purposes only.

I claim:

The ornamental design for an electrical wiring device or similar article, substantially as shown and described.
